EUGÈNE RAGOT, OF BETTAINCOURT, AND PAUL PIERRE-HERVOTTE, OF JOINVILLE,
HAUTE-MARNE, FRANCE.

GAS-PRODUCER.

1,083,507.

Specification of Letters Patent.

Patented Jan. 6, 1914.

Application filed October 15, 1912. Serial No. 725,779.

To all whom it may concern:

Be it known that we, EUGÈNE RAGOT and PAUL PIERRE-HERVOTTE, citizens of France, residing, respectively, at Rue de la Gare, 5 5 Bettaincourt, and 10 Rue des Royaux, Joinville, Haute-Marne, in the Republic of France, have invented new and useful Improvements in Gas-Producers, of which the following is a specification.

10 This invention relates to gas producers containing two superposed combustion zones and has for object an improved producer consuming fuels of the most diverse nature either alone or mixed, such as saw-dust, 15 wood waste, charcoal dust and other fuel waste.

The invention consists in the arrangement that the lowermost of the two superposed combustion zones, where the most intense combustion takes place is arranged immediately above a water cistern, so that the gases produced are compelled to pass immediately through the water before reaching the exhaust flue. The chief advantage 25 of this arrangement is that it permits of utilizing fuels of a nature rendering them quite useless in ordinary producers, this being due to the fact that the escaping gases are immediately washed as soon as they 30 leave the interior of the producer, the ashes and other solid particles carried away with said gases being immediately arrested in the water, so that the exhaust channels into which the gas is directed are not liable to 35 be obstructed by the solid particles, which would invariably take place in gas producers already known, in view of the considerable amount of solid particles carried away with the gas when low grade fuels such as above 40 cited are used.

One example of the improved gas producer is illustrated in the accompanying drawings in which, Figure 1 is an elevation, Fig. 2 is a horizontal section of the grate, 45 Fig. 3 is a detail in vertical section of the cistern, Fig. 4 is a vertical section of the whole producer at the line 4-4 of Fig. 5. Fig. 5 is a horizontal section at the line 5-5 of Fig. 4.

50 The walls 1 of the producer are of fire-proof material and are surrounded by a metal envelop 2. The producer is mounted on a water cistern 3 and supports at the top

another water cistern or tank 4 for supplying the water injected along with the blast 55 into the producer when utilizing certain fuels. The producer also supports a charging platform 5 of the usual construction.

The inside of the gas producer has the form shown in the drawing that is of four superposed conical sections united at their base, the small upper base forming the charging opening being normally closed by a cover 6. At the small lower base is fitted a perforated cylindrical member 7 supporting the grate bars 8. This grate is in three pieces (Fig. 2) the center part being capable of sliding to permit of cleaning. This formation of the inside of the producer gives rise to two combustion zones at 9 and 10 and provides a double inverted combustion when the lower combustion zone 10 is the seat of the more intense heating. The upper zone is fed with air by four supply openings 11 arranged 90° apart one of which 11^a is of larger diameter than the others and gives access to the interior of the producer. The lower zone is fed with air by four other similar openings 12 displaced by 45° with respect to the upper openings. The opening 12^a is of larger size than the others and is closed by a door 17 which facilitates the breaking up of the fuel when necessary in the lower zone of the producer. A removable fire proof block 18 is provided which may be taken out to facilitate access to the 70 lower zone.

All the openings 11 and 12 are connected by vertical pipes 13 with a common annular receiver 14 arranged near the top of the producer and obtaining its supply at 15 in 90 any suitable manner. Valves 16 enable the air injected into the different parts of the producer to be regulated at will.

The lower zone 10 of the producer is located immediately above the water filling 95 the cistern 3, which would rise above the grate bars 8 were it not prevented from doing so by the pressure of the air. This system at one part of its periphery is provided with an outlet tank 3^a (Figs. 3 and 5) comprising a pipe connection 19 for the outlet of the gas which proceeds first to a washing device and then to a purifier. A vertical partition 20 projects into the water and normally prevents the gas from flowing out 100 105

through the open duct 21 at the top of the tank. The object of this duct is to enable the gas to escape in case of an accumulation of gas caused by a stoppage or other reason, 5 this arrangement thus avoiding explosions.

The producer having been charged with fuel and the bellows started the gases generated move downward through the fuel and first arrive at the upper zone 9 where a first 10 combination takes place; continuing their descent they pass through the incandescent mass at the lower zone 10, where the temperature is higher, and the heavier materials, oils, tars, and the like entrained by the gases 15 are finally volatilized and completely burned.

Owing to this double inverted combustion the gases arriving at the water cistern 3 are thus comparatively pure and all materials capable of caking and obstructing the grate 20 bars and other parts of the grate, are burnt.

Should however caking occur and a breaking up of the fuel be necessary, this can be very easily effected without a prolonged stoppage of the operation of the producer.

25 It is only necessary after having stopped the air injection, to remove the block 18 and introduce through the door 17 of the passage 12^a iron rods adapted to support the charge of fuel inside the producer. The moving 30 part of the grate bars 8 is then drawn out so as to allow the fuel in the lower zone to fall into the cistern 3 whereupon the wall of said zone is easily cleaned. The producer is started again without difficulty.

35 The gas on issuing from the lower zone 10 passes through the perforations of the plate 7, and the grate bars and comes in contact with the water in the cistern 3 and bubbles through this water becoming washed and 40 cooled in the process. It escapes as has been described into the lateral tank 3^a and the pipe 19. The ashes and fine solid particles carried away with the gases are thus retained in the water and prevented from clogging 45 into the exhaust pipes. Pipes not shown enable the air injected to be mixed

with a suitable quantity of water from the upper tank 4.

We claim:

1. In a gas producer, in combination: a 50 producer shaft having a restricted cross section at the bottom and at a point intermediate its height, means for closing said producer shaft at the top, means for admitting air into said producer shaft at points immediately above the restricted portions thereof, and thus forming in the producer two superposed combustion zones, a water cistern located immediately beneath the lower combustion zone so that the gases 60 leaving the producer are compelled to first pass through the water and an exhaust pipe for the gas, connected to said water cistern at the outside of the lower opening of the producer shaft, substantially as described 65 and for the purpose set forth.

2. In a gas producer, in combination: a producer shaft having a restricted cross section at the bottom and at a point intermediate its height, means for closing said producer shaft at the top, a grate at the bottom of the same, means for admitting air into the producer shaft at points immediately above the restricted portions thereof, and thus forming in the producer two superposed combustion zones, a water cistern closed at the top and containing water in which the grate is adapted to be submerged, an exhaust pipe for the gas, connected to the top of said water cistern at the outside of 80 the grate, and a lateral tank open at the top and communicating at the bottom with the water cistern, substantially as described and for the purpose set forth.

In testimony whereof we have signed our 85 names to this specification in the presence of two subscribing witnesses.

EUGÈNE RAGOT.

PAUL PIERRE HERVOTTE.
